DESIGN FOR A COMBINED FLOOR LAMP AND DISPLAY DEVICE

Ignazio Latella, Port Chester, N. Y.

Application March 1, 1944, Serial No. 112,758

Term of patent 14 years

(Cl. D80—9)

To all whom it may concern:

Be it known that I, Ignazio Latella, a citizen of the United States, residing at Port Chester, in the county of Westchester and State of New York, have invented a new, original, and ornamental Design for a Combined Floor Lamp and Display Device, of which the following is a specification, reference being had to the accompanying drawing, forming a part thereof.

Figure 1 is a front elevational view of a combined floor lamp and display device, showing my new design;

Figure 2 is a side elevational view; and
Figure 3 is a top plan view thereof.

I claim:

The ornamental design for a combined floor lamp and display device, as shown.

IGNAZIO LATELLA.
